ABSTRACT

An improved toggle operated plunger clamp having control means for inhibiting the movement of the plunger when unloaded. The control means includes adjustable collet and adjustable key means operative to engage the clamp at intermediate positions as well as auxiliary retaining means operative in both the fully closed and fully open positions when the plunger is otherwise unloaded.

PLUNGER CLAMP

BACKGROUND OF THE INVENTION

Plunger clamps have a clamping member reciprocably movable back and forth in a clamp body which in turn is usually anchored to a fixture. Such clamps utilize a simple toggle linkage attached to the plunger and the body to reciprocate the plunger and toggle lock the plunger at its extreme extended or retracted position when in engagement with a workpiece respectively as a push clamp or a pull clamp. The plungers of such clamps normally have clearance in the body to allow freedom of reciprocal movement. This frequently leads to undesired gravity actuation of the clamp at intermediate unloaded positions. Furthermore, a loose fit may be unsatisfactory and detrimental to accurate clamping of the workpiece.

SUMMARY OF THE INVENTION

The invention comprises an improved toggle operated plunger clamp including control means to inhibit unloaded movement of the plunger. The control means include adjustable means to eliminate undesirable looseness of the plunger while allowing for required reciprocal action and auxiliary retention means for the fully extended and retracted positions. The initial positioning accuracy and firm workpiece positioning of the clamp is greatly enhanced and retained over relatively long usage by the combination of a split collet adjustment to counteract transverse looseness and a hardened key and flat adjustment to counteract rotational looseness. An adjustable lock nut is provided on the plunger to engage a shoulder on the body thereby providing a stop for toggle locking action in the fully extended plunger position when a workpiece is not engaged. Conical depressions in the toggle linkage engageable with conical "belleville" spring washers provide auxiliary retention for the fully retracted position even in the absence of workpiece loading.

DESCRIPTION OF THE DRAWINGS

FIG. 1 is a side elevation of the plunger clamp showing portions cut away for clarity;

FIG. 2 is a top elevation of the plunger clamp showing portions cut away for clarity; and,

FIG. 3 is a partial end elevation of the plunger clamp.

DESCRIPTION OF THE PREFERRED EMBODIMENT

As shown, the clamp includes a body 10 substantially cylindrical in shape and welded or otherwise attached to a base 12. The base 12 includes holes 14 for bolts or other fastening means suitable for attachment to a supporting structure, not shown. The cylindrical body 10 may be welded to the base 12 in any rotative position desired. Concentrically located in the body 10 is a plunger 16 having a threaded bore hole 18 suitable for fastening fixture means as desired. The body 10 includes a concentric bore hole 20 extending from the end 24 of the body. A flat 22 is formed on the body 10 and also extends from the end 24. The flat 22 intersects the bore hole 20 to form the opening 26. The opening 26 is broadened further at 28 to provide clearance for the yoke 30 of the handle 32. A pivot pin 34 is located in a bore hole 36 passing through the body 10 and the

yoke 30 to provide a pivot for the handle 32. A second pin 38 located in a bore hole 40 through both sides of the yoke 30 provides a pivot for one end of the toggle link 42. The other end of the toggle link 42 in turn is attached to the plunger 16 by a pivot pin 44 located in a bore hole 46 through the fork 48 of the plunger 16 and the toggle link 42.

The plunger 16 is centered in the body 10 by a collet 50. The collet 50 is split at 52 and engages a conical bore hole 54 in the plunger end 25 of the body 10. The collet 50 also engages the body 10 in the threaded bore at 56. The inner bore 58 of the collet 50 squeezingly engages the plunger 16. Thus, the collet 50 can be adjusted to take up all clearance, inhibit and eliminate transverse play of the plunger 16 relative to the body 10 and provide desired frictional retention merely by turning the collet with a wrench in engagement with the hexagonal end 60 of the collet.

The plunger 16 includes a flat 62 best shown in FIG. 2, which extends the greater part of the length of the plunger and engages a hardened key 64 in the shape of a disc, as shown in FIGS. 1 and 2. The disc 64 is set in transverse shoulder bore 66 formed in the wall of the bore hole 68. A set screw 70 located in a threaded hole 72 in the body 10 adjustably applies a force to the key 64 and flat 62 thereby taking up all clearance, inhibiting the rotational of play of the plunger 16 and providing additional desired frictional retention. Alternately twin set screws laterally spaced on either side of the vertical plane containing the plunger axis and engaging the key 64 may be provided.

The bore hole 68 intersects the bore hole 20 to form a shoulder 74. The shoulder 74 is engageable with a circular nut 76 threaded on the fork 48 of the plunger. The nut 76 includes a plurality of holes 78 adapted for the insertion of a metal pin to turn the nut. The nut 76 is suitably adjusted for engagement with the shoulder 74 for tight toggle locking action when the plunger is unloaded, as shown in solid outline in FIG. 1 thereby providing auxiliary end position retention for unloaded plunger. When the plunger 16 is loaded by a workpiece, the resistance of the workpiece provides the necessary force for tight toggle locking action and the nut 76 is therefore not in forceful engagement with the shoulder 74. After proper adjustment of the nut 76, it may be permanently retained in position by any of the conventional hardenable glues for setting a nut in permanent position.

The link 42 includes a downwardly open ended slot 80. The slot 80 is adapted to fit over the central portion of the pin 34 when the clamp is in fully open position, as shown by the phantom outline 82 of the toggle link 42 and handle 32. A conical depression 84 surrounds the closed end of slot 80 on either side and is located in the shallow bore 86 which surrounds the slot 80, except for the open end thereof. The conical bore 84 on each side of the slot 80 is engageable with the twin opposed belleville washers 88 mounted on the pivot pin 34. A small collar 90 retains the belleville washers 88 separated and against the yoke 30, as shown clearly in FIG. 2. The conical bore 84 and slot 80 are so related that the conical bore 84 is substantially more than 180° in arcuate extent from the corner 92 to the corner 94 on either side of the slot 80. Therefore, when the clamp is fully opened and the slot 80 in the link 42 pulled down over the shaft 32 and collar 90, the belleville washers 88 are resiliently spread by the corners 92 and

94 before snapping into place in the conical depressions 84. This produces the snap action auxiliary retention for the fully open position thus assuring that the handle and plunger will not move under vibration or otherwise than by intentional operation when the plunger is fully retracted.

We claim:

1. An improved double action toggle plunger clamp comprising a body, a plunger adapted for reciprocal movement within said body, toggle actuating means adapted to reciprocate said plunger and lock same in either fully extended or fully retracted position when said plunger is subjected to an opposing axial load, and characterized by control means to inhibit the unloaded movement of said plunger, said control means including adjustable frictional means interengaging between said body and plunger at intermediate positions of said plunger, additional control means for retaining said plunger at one extremity position when said plunger is not subjected to an opposing axial load rendered inoperative when said plunger is subjected to an opposing axial load, and further additional control means for retaining said plunger in its other extremity position where it is not subjected to an opposing axial load.

2. The plunger clamp of claim 1 wherein said control means includes means to remove rotational lost motion of said plunger.

3. The plunger clamp of claim 1 wherein said control means includes a longitudinally extending flat on said plunger and an adjustable key member positioned in said body and adapted to engage said flat to remove rotational lost motion of said plunger.

4. The plunger clamp of claim 1 wherein said additional control means includes a shoulder in said body and adjustable nut means on said plunger adapted to engage said shoulder upon reciprocation of said plunger to one extremity of movement.

5. The plunger clamp of claim 1 wherein said further additional control means includes a conical depression in said actuating means and conical spring washer means on said body adapted to engage said conical de-

pression upon reciprocation of said plunger to one extreme of movement.

6. The plunger clamp of claim 1 wherein said adjustable means includes collet means engaging said body and adapted for adjustable tightening about said plunger to remove transverse lost motion of said plunger.

7. The plunger clamp of claim 6 wherein said control means includes a longitudinally extending flat on said plunger and an adjustable key member positioned in said body and adapted to engage said flat to remove rotational lost motion of said plunger.

8. The plunger clamp of claim 1 wherein said further additional control means includes a slot in said actuating means, a conical depression extending about one end of said slot and conical spring washer means on said body adapted to engage said conical depression upon reciprocation of said plunger to one extremity of movement.

9. The plunger clamp of claim 8 wherein said conical depression extends more than 180° about the closed end of said slot.

10. An improved plunger clamp comprising a body, a plunger adapted for reciprocal movement within said body, actuating means adapted to reciprocate said plunger, said actuating means including a handle pivotally mounted on said body and a toggle link pivotally attached to said handle at one end and pivotally attached to said plunger at the other end, adjustable collet means concentrically mounted in said body about said plunger, a longitudinally extending flat in said plunger, an adjustable key member positioned in said body and engaging said flat, a shoulder in said body and adjustable nut means on said plunger adapted to engage said shoulder at one extreme of movement of said plunger, a slot opening in said toggle link having a conical depression extending about the closed end of the slot, and conical spring washer means on said body adapted to engage said conical depression at the other extreme of movement of said plunger.
